UNITED STATES PATENT OFFICE.

WILLIAM C. WINFIELD, OF WARREN, OHIO.

GLOBE-RAISING MECHANISM FOR TUBULAR LANTERNS.

SPECIFICATION forming part of Letters Patent No. 634,076, dated October 3, 1899.

Application filed January 19, 1899. Serial No. 702,691. (No model.)

To all whom it may concern

Be it known that I, WILLIAM C. WINFIELD, a citizen of the United States, residing at Warren, in the county of Trumbull and State of Ohio, have invented certain new and useful Improvements in Tubular Lanterns; and I do declare that the following is a full, clear, and exact description of the invention, which will enable others skilled in the art to which it applies to make and use the same.

My invention relates to tubular lanterns; and the object of the invention is to provide means whereby the globe can be easily raised for lighting the lantern and lowered again to its seat, and also whereby the canopy and globe can be conveniently tilted for the removal and replacement of the globe, all as hereinafter fully described, and particularly pointed out in the claims.

In the accompanying drawings, Figure 1 is a side elevation of my improved lantern having part of the lifting mechanism in section and the globe seated. Fig. 2 is a side elevation of the lantern at right angles to Fig. 1, with the tubular frame broken away on the near side and the canopy and central tube in section, giving a view on line 2 2, Fig. 1. Fig. 3 is a plain elevation of the lantern with the globe raised and certain parts in section; and Fig. 4 is a plain elevation at right angles to Fig. 3 with the near tube broken away and the lift mechanism and globe up, as shown in Fig. 3. Fig. 5 is a cross-section on line x x, Fig. 4, looking down on the canopy; and Fig. 6 shows the canopy tilted. Fig. 7 is a modification of the lifting mechanism.

Referring to the lift mechanism for the globe, I am of course aware that, broadly, such mechanism is not new, and I have seen devices serving this purpose which in some cases operated from beneath the globe and in others from above or about the top of the globe. Then, again, there are numerous devices to tilt the globe to effect lighting.

A represents the tubular portion of the lantern, and B the globe.

C are carrying and guide wires for the globe, connected with the globe-supporting plate D at the bottom and with the canopy E at the top. The connections with the canopy and the plate D are rigid, as here shown, so that, in a sense, the wires C, plate D, and canopy E

are one rigid structure and frame adapted to move together as one and carry and support the globe. The said wires C are each shown as bent inward at right angles at their lower ends and forming horizontal portions c, which either engage directly with the plate D or are extended more or less around the edge of said plate. One of said wires is also bent higher up to form an offset or shoulder c', and the tubular frame or tubes A have guides a on their inner side, about midway their height, which serve to confine and guide the wires C, especially when the globe is raised and lowered. As many such guides a may be used as are deemed best; but two suffice to keep the globe and frame in place, and they serve especially when the globe is being raised and lowered.

Now in order to effect the direct up-and-down movements of the globe contemplated by my invention a simple mechanism is required, consisting of the substantially elbow-shaped member G, pivotally connected at its top on the shoulder c' and having a segmental slot g in its lower portion engaged and working on the horizontal portion of the side wire. Then in order to utilize said part G in the raising and lowering of the globe I employ a double bell-crank lever H, which is pivoted on the side of the tube A and has a handle portion h outside and its inner portion h' engaged in the part G at or near the angle therein and at one end of the segment-slot g.

In operation when the globe is to be raised the elbow G is swung by lever H first the full length of the slot g from the down and closed position seen in Fig. 2 to the other end of the slot, as shown in dotted lines, Fig. 4. This movement of elbow G and its slot g is far enough for the bell-crank lever H to describe part of a complete circle of rotation and is the extreme of its outward movement. From this point the movement is upward and inward until the half-circle of movement has been described and the parts are brought to full lines, Fig. 4. Here the bell-crank is shown as swung a little past the center to lock the parts. In like manner when the globe is down the lever swings past the center a little and locks the globe-frame in its lowered position.

Referring to Fig. 4, it will be seen that the elbow occupies the same relation to the parts

as it does in Fig. 1, and one is the raised and the other is the lowered position. Meantime to get either position from the other the elbow must traverse the full length of its curved slot or channel twice—back and forth—because it has just length enough to accommodate itself to the successive quarter-turns of the bell-crank lever.

Obviously the foregoing arrangement of parts could be inverted and serve identically the same purpose—that is, the part G could be pivoted on the horizontal wire c and the segment engaged on shoulder c' and the lever H be moved up correspondingly. The same half-rotation of lever H would be effected with the same results, and hence it is immaterial which way the parts are arranged.

Another novel feature of construction is the canopy E and the shield or collar L, connected therewith. The canopy has an oblong hole in its center for the central draft-tube K of the lantern, and the collar L has a central free but round opening for said tube. Keepers k' on the canopy confine the collar L, and the construction and arrangement of these parts are such that the canopy has a limited tilting movement—for example, about as seen in Fig. 6. The side wires C have spring enough to allow this to be done even though they are rigid with and not pivotally attached to the canopy. When the globe has been removed, the spring of the wire presses the canopy back to central position again. Meantime the plate L serves as a shield to the oblong opening in the canopy and effectually closes the canopy about the central tube K.

In order that the handle M may be held upright, I have extended the end m thereof inward horizontally over the horizontal portion 40 of the tube A and provided said tube with a depression, Fig. 2, into which the extension m springs and locks sufficiently to sustain the handle, as in Fig. 1.

It will be seen that when the arm of the lever H is horizontal the segmental slot g will have reached its outer limit, so that any further movement of said lever will cause a retrograde movement of said slot.

What I claim is—

50 1. In tubular lanterns means to raise and lower the globe comprising the frame, a pivoted lifting part engaged at two points on

said frame, and a pivoted lifting-lever connected with said pivoted lifting part, substantially as described.

2. The tubular frame and the globe-frame, in combination with a member pivoted at one end on the globe-frame and constructed at its other end with a curved channel to swing on said frame within fixed limits, and a lifting-lever journaled on the adjacent air-tube and connected with the swinging end of the said member to lift and lower the globe-frame, substantially as described.

3. The air-tubes and the globe and its carrying-frame, in combination with a rotatable lifting-lever journaled on one of the air-tubes and a swinging part pivoted at one end on said frame and having a curved slot at its other end working on said frame, and the said lifting-lever connected at its inner end with said swinging member, substantially as described.

4. The tubes and the globe-frame, in combination with a rotatable lifting-lever on one 75 of said tubes, and a lifting member connected near its lower end with said lever and pivoted on the side of the globe-frame at the opposite end from its engagement with the lifting-lever, said member having a segmental slot 80 within which is confined a substantially horizontal portion of the globe-frame, substantially as described.

5. In a lantern, the tubular frame and central draft-tube, in combination with the canopy having an oblong opening about said draft-tube and a plate engaged on the under side of the canopy and extending around the draft-tube to close the oblong opening in the canopy, substantially as described.

6. The tubular frame having a depression in its upper portion, in combination with the wire bail looped around said frame and having one of the ends of the wire extending outside of its loop around the frame and bent to a substantially horizontal position to lie normally in said depression, substantially as described.

Witness my hand to the foregoing specification this 31st day of December, 1898.

WILLIAM C. WINFIELD.
